UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,327,788.

Specification of Letters Patent. Patented Jan. 13, 1920.

Application filed May 31, 1919. Serial No. 300,952.

To all whom it may concern:

Be it known that I, EDWARD S. STIMPSON, of Hopedale, in the county of Worcester and State of Massachusetts, have invented a 5 new and Improved Feeler Mechanism for Looms, of which the following is a specification.

In many weaving mills the same loom is frequently used when weaving both with 10 weft wound on bobbins and with cops. The side slipping type of feeler (which feels for the weft within the shuttle at the detecting side of the loom and slips laterally along the bared bobbin when the weft is nearly exhausted and thereby initiates the action of 15 weft replenishing mechanism) is admirably adapted for use when the weft is wound upon bobbins, but is not efficient with cops. The yarn is commonly wound at the base of 20 the cop upon a quill or cop tube of paper. This paper tube is sufficiently rough so that the feeler does not always slip on it when the weft approaches exhaustion so that weft replenishment does not take place and 25 the function of the feeler mechanism is destroyed. The object of the present invention is to adapt the side slipping feeler for use with cops. The improved feeler when 30 used with weft wound on bobbins acts in the normal way of side slipping feelers; but, when used with cops, it is in effect a "measuring" feeler depending for its action upon the distance between the nearly depleted 35 mass of weft and a fixed datum surface, such as the outer face of the front wall of the shuttle. The improved feeler is provided with a shuttle feeling finger which contacts with the outer surface of the front 40 wall of the shuttle when the weft is depleted to the predetermined minimum and then slips laterally along the smooth surface of the shuttle thereby bringing into action the weft replenishing mechanism.

The improved feeler mechanism is illustrated in the accompanying drawings, 45 wherein—

Figure 1, is a plan view of the feeler mechanism and of a portion of the shuttle box at the detecting end of the lay. Fig. 2, 50 is an enlarged view of the feeling end of the feeler. Fig. 3, is a vertical cross-section in the plane indicated by the line 3—3 in Fig. 1. Fig. 4, is a plan view of the mechanism illustrating the weft depleted to the pre- 55 determined minimum and the shuttle feeling

finger in its initial contact with the front wall of the shuttle box. Fig. 5, is a vertical cross section in the plane indicated by the line 5—5 in Fig. 4. Fig. 6, is a view similar to Fig. 4, illustrating the feeler at the conclusion of the side slip of the shuttle feeler finger upon the front wall of the shuttle. 60

As shown in the drawings, A, is the side slipping feeler having a toothed weft feeling tip B which contacts with the weft C 65 when the lay D beats forward with the shuttle E in the box at the detecting side of the loom. Figs. 1 and 2, illustrate the contact between the weft and this tip when the weft is present in adequate volume. 70 Should the weft be wound upon a bobbin, then when the weft is so far depleted as to expose the smooth surface of the bobbin to the weft feeling tip, the feeler would slip laterally, as in prior feelers of this type, 75 such as that shown, for example, in Letters Patent of the United States, No. 1,309,226, July 8, 1919.

The present drawings illustrate a cop with weft wound upon its base in the usual 80 manner upon a paper quill or cop tube F. The toothed weft feeling tip will not slip with certainty upon this cop tube. Therefore, in order to adapt the feeler for use with cops, it is provided with a shuttle feeling finger G. As shown, this feeling finger is the smooth head of a screw which adjustably screws into a vertically extending standard H, fastened to the top of the feeler A, so that the finger is forward of the weft 90 feeling tip. The shuttle feeler finger is held in any position of adjustment on the standard H by means of a lock nut P.

As shown in the drawings, the feeling end of the feeler passes through a slot R in the 95 front wall S of the shuttle, but the shuttle feeling finger G extends above the slot R, so that it is adapted to be encountered by the front surface of the front wall of the shuttle when the weft is sufficiently depleted, 100 as indicated in Figs. 4 and 5. When the weft is so far depleted that it affords no effective resistance to the toothed weft feeling tip, the shuttle feeling finger encounters the smooth outer surface of the front wall 105 of the shuttle and slips laterally thereon, thus initiating the action of the weft replenishing mechanism. By adjustment of the shuttle feeling finger on the feeler, the amount of weft in the shuttle at the time 110

the side slip of the feeler takes place can be predetermined so that there will be still enough weft left following the side slip to insure the replenishment of the weft before the running weft is entirely exhausted.

So far as the action of the feeler is concerned, when cops are employed, the feeler is in effect a measuring feeler, depending upon the distance between the surface of the 10 depleted weft and a fixed datum surface, such as the front wall of the shuttle. But, as a measuring feeler the present mechanism possesses an important advantage. The weft commonly wound on cops is soft and a 15 feeler finger sinks into it, so that ordinary measuring feelers are apt to initiate weft replenishment prematurely so that a large portion of the weft is wasted. With the present mechanism, the softness of the weft 20 is not a disturbing factor because the critical action of the feeler takes place when the shuttle feeler finger effectively encounters the smooth front wall of the shuttle and the amount of weft then in the shuttle can be 25 closely predetermined, thereby reducing the waste to a minimum.

The side slipping finger to which the improved shuttle feeling finger is secured may be of any of the types now employed. It 30 may be a feeler of the impact type wherein the weft feeling tip is offset laterally with respect to the feeler support so that the impact of the weft upon the feeler tends to displace it laterally, such displacement being 35 prevented by the friction of the weft when present in sufficient quantity, the side slip occurring when the smooth surface of the bobbin encounters the weft feeling tip. Or the side slipping feeler may be of the 40 type wherein it is subjected to the lateral pull of a spring which tends to displace the feeler sidewise. In the accompanying drawings, the shuttle feeling tip is shown as applied to the impact type of side slipping 45 feeler which in the respects not yet described is like that disclosed in the aforesaid patent No. 1,309,226. Enough of the coöperating feeler mechanism of that application is shown in the accompanying drawings to 50 enable the side slipping characteristics to be understood.

The feeler A is mounted on a bracket I attached to a lateral extension J of the breast beam. A front guide K is swiveled 55 to the forward end of the bracket and turns on a vertical axis. This front guide has an aperture through which the front end of the feeler extends and slides. Near its rear end the feeler extends through a broad guide 60 way L in the bracket. The top of this guide way is closed by a cap M, which with the bottom of the bracket confines the feeler against vertical movement. Secured to the feeler near its middle is a slide N which 65 slides on horizontal ways O of the bracket.

A spring Q, surrounds the feeler between the slide N, and the swiveled guide K, and normally holds the feeler arm in its rearward position (shown in Fig. 1) with the slide against the shoulders of the bracket 70 which supports the cap M. The feeler arm is also maintained by the spring against the outer wall of the rear guide way. The swiveled guide and the outer wall of the rear guide way are offset laterally with respect 75 to the feeler tip so that the weft encounters the tip along a fore and aft path laterally displaced or offset with respect to the paths intersecting the guides. So long as the weft encounters the teeth of the weft feeling tip 80 the resistance thus offered prevents any slipping of the tip due to the impact of the weft. Accordingly, as the lay moves forward, after the first encounter of the weft with the tip, there is no slipping of the tip 85 along the weft; but during the completion of the forward movement of the lay the feeler is moved forwardly compressing the spring Q. During this normal action there is a slight swing to the right of the feeler 90 permitted by the turning of the swiveled guide K. When the shuttle feeling finger is encountered by the front wall of the shuttle, the impact of the shuttle causes a further lateral swing of the feeler to the 95 right, as shown in Fig. 6, and this additional lateral swing is at least sufficient to set in action the train of weft replenishing mechanism. This functional swing of the feeler under the impact of the shuttle causes the 100 feeler to encounter a controller X, and move it laterally. This controller is mounted in a transverse guide way Y, of a bracket J, and it has a slot Z, through which the feeler passes. This slot is sufficiently wider than 105 the feeler so that the normal swing of the feeler has no effect on the controller. When, however, the functional swing of the feeler is imparted to it by the movement of the shuttle feeling tip along the front wall of 110 the shuttle the controller is slid laterally. This lateral movement of the controller is utilized to bring about weft replenishment as explained in detail in the aforesaid patent. After the functional action has 115 occurred a fixed cam W, acts upon a downwardly extending projection V, indicated in dotted lines only in Fig. 6, on the feeler, to restore the feeler to its normal position as it retreats under the influence of the spring Q, as set forth in said application.

No adjustment of the shuttle feeling finger G is required when the improved feeler mechanism is to be used upon weft wound upon bobbins. The greater diameter 125 of the bobbin as compared with that of the cop tube insures that the toothed weft feeling tip will be encountered by a bared bobbin before the shuttle feeling finger reaches the shuttle front. Accordingly, 130

when the feeler mechanism is used with weft wound on bobbins, the action is just the same as in the aforesaid patent, wholly unaffected by the presence of the shuttle feel-
5 ing finger.

Instead of the auxiliary finger acting upon the shuttle wall, it might (less desirably) act upon another smooth datum surface, such as the front wall of the shuttle
10 box.

I claim:

1. A feeler mechanism for looms having a side slipping feeler with a toothed weft feeling tip, in combination with a vertical standard secured to the top of the feeler near its tip end, and a shuttle feeling finger adjustably mounted on said standard with its shuttle feeling end forward of the toothed weft feeler tip, said shuttle feeling finger
15 being adapted to be encountered by and to slip laterally upon the front wall of the shuttle when the weft feeling tip does not make restraining contact with the weft.

2. A feeler mechanism for looms having a side slipping finger with a toothed weft feeling tip, in combination with a shuttle feeling finger adjustably mounted on the feeler with its shuttle feeling end forward of the toothed weft feeler tip, said shuttle feeling finger
25 being adapted to be encountered by and to slip laterally upon the front wall of the shuttle when the weft feeling tip does not make restraining contact with the weft.

3. A feeler mechanism for looms having a side slipping feeler with a weft feeling tip, in combination with a shuttle feeling finger mounted on the feeler with its shuttle feeling end forward of the weft feeler tip, said shuttle feeling finger being adapted to be
35 encountered by and to slip laterally upon the front wall of the shuttle due to the impact thereof when the weft feeling tip does not make restraining contact with the weft.

4. A feeler mechanism for looms having a side slipping feeler with a laterally off-
45 set weft feeling tip, in combination, with a

laterally offset shuttle feeling finger mounted on the feeler with its shuttle feeling end forward of the weft feeler tip, said shuttle feeling finger being adapted to be encountered by and to slip laterally upon the front wall of the shuttle due to the impact thereof when the weft feeling tip does not make restraining contact with the weft.

5. A feeler mechanism for looms having a side slipping feeler with a weft feeling tip, in combination with a vertical standard secured to the top of the feeler near its tip end, and an auxiliary feeling finger mounted on the feeler forward of the weft feeler tip, said auxiliary feeling finger being adapted to be encountered by and slip laterally upon a smooth surface due to the impact thereof when the weft feeling tip does not make restraining contact with the weft.

6. A feeler mechanism for looms having a side slipping finger with a toothed weft feeling tip, in combination with a vertical standard secured to the top of the feeler near its tip end, and a shuttle feeling finger movably and adjustably mounted in said standard with its shuttle feeling end forward of the toothed weft feeler tip, said shuttle finger being adapted to encounter and slip laterally upon the front wall of the shuttle when the weft feeling tip does not make restraining contact with the weft.

7. A feeler mechanism for looms having a side slipping feeler with a weft feeling tip, in combination with an auxiliary feeling finger mounted on the feeler forward of the weft feeler tip, said auxiliary feeling finger being adapted to be encountered by and slip laterally upon a smooth surface due to the impact thereof when the weft feeling tip does not make restraining contact with the weft.

In witness whereof, I have hereunto signed my name.

EDWARD S. STIMPSON.
